UNITED STATES PATENT OFFICE.

FRANK VOGEL, OF NEW WASHINGTON, OHIO.

FILE FOR HANDLING REGISTERED MAIL, PARCEL POST, AND C. O. D. PACKAGES.

Application filed November 11, 1925. Serial No. 68,437.

This invention appertains to a novel device for handling registered mail and a novel method of using the device, so that a record can be readily kept of registered mail.

5 The primary object of the present invention is to provide a novel device of compact structure for facilitating the handling of registered mail and the like in banks and other business houses, the device being so constructed as to not only facilitate the handling of such mail, but also permit a thorough record to be kept thereof so as to prevent the occurrence of errors in handling such mail.

Another object of the invention is to provide a novel device, having compartments arranged therein for the reception of sealing wax, clips, matches and the like for facilitating the sealing of registered letters and packages and a main compartment having filing pins arranged therein for the reception of record envelopes or the like, which are adapted to receive indicia relative to the registered mail, the envelopes being adapted to be transferred from one set of filing pins to the other according to whether the return receipt is in or still awaiting return.

Another object of the invention is the provision of novel means for constructing the last pair of filing pins for receiving the record envelopes in which the return receipts have come in, so as to permit the easy binding of these record envelopes into bundles to permit the same to be stored away in a place for safe keeping.

35 A further object of the invention is the provision of novel means of arranging the filing pins in the device, so that the pins will be engaged by the cover of the device when the same is in its lowered position, thereby effectively preventing displacing and loss of the record envelopes from off of the said filing pins.

A still further object of the invention is the provision of partitions carried by the cover corresponding to the partitions carried by the body of the device, whereby the various implements placed within the compartments will be retained in their respective compartments without becoming displaced therefrom and mixed together irrespective of the position in which the device may be carried.

55 A still further object of the invention is to provide an improved device for handling registered mail and for keeping a complete record thereof, which will be durable and

efficient in use, one that will be simple and easy to manufacture, and one which can be placed upon the market at a reasonable cost.

With these and other objects in view, the invention consists in the novel construction, arrangement and formation of parts, as will be hereinafter more fully described, claimed, and illustrated in the accompanying drawings, in which drawings:

60 Figure 1 is a plan view of the improved file or case showing the cover thereof in its raised position and the record elements in certain positions that they occupy at an intermediate stage in the use of the device.

65 Figure 2 is a longitudinal central section through the improved device, illustrating the method of using the same and showing the cover thereof in its raised position.

70 Figure 3 is a transverse section through the improved device illustrating the compartments at the forward end thereof and showing the cover in its lowered position.

75 Figure 4 is a similar section taken through the rear end of the device showing the cover in its closed position and illustrating the arrangement of the rear pair of filing pins for receiving the record envelopes after the registered mail has been delivered and the return receipt redelivered to the sender.

80 Figure 5 is a plan view of one of the binding back cards utilized for binding the record envelopes together in which the transactions have been completed and the envelopes have been collected for a predetermined length of time.

85 Figure 6 is a perspective view showing a package of the record envelopes tied together.

90 Figure 7 is a detail diagrammatic view illustrating the use of the rear pair of binding pins for facilitating the binding of a pack of the record envelopes together.

95 Figure 8 is an enlarged plan view of one of the record envelopes which can be employed in the handling of parcel post packages which are to be registered or insured.

100 Referring to the drawings in detail, wherein similar reference characters designate corresponding parts throughout the several views, the letter A generally indicates the improved device, which comprises a filing cabinet or case 10. This cabinet or case 10 can be formed of any desired size and from any preferred material, but it is desired to construct the same of a convenient size to permit the easy handling thereof and of light material such as cast aluminum. The case 10 com-

prises a rectangular shaped body 11 including the spaced side walls 12 and 13, the end walls 14 and 15, and the bottom wall 16. This bottom wall 16 can be provided with enlarged 5 openings 17 at appropriate points, as will be herinafter pointed out in order to reduce the weight of the case or cabinet. This bottom wall 16 supports adjacent to the front and rear ends thereof suitable rubber feet or 10 cushioning legs 18' in order to prevent the marring of the surface on which the case is placed. The body 11 is divided by a longitudinally extending partition 18 which is arranged adjacent to but in spaced parallel relation to the side wall 13 and the space defined between the partitions 18 and the side wall 13 is again divided by a transverse partition 19 which is arranged adjacent to the front wall 14. A second transversely extending partition 20 15 is arranged within the body of the box and this partition is arranged adjacent and in spaced parallel relation to the front wall 14 and extends from the side wall 12 to the partition 18 and the space defined by the partition 20 and the front wall 14 is divided by a partition 21 into a card-receiving chamber 23 and a match box receiving chamber 24. The partition 18 and the transverse partition 19 in connection with the walls of the box define an 20 elongated longitudinally extending compartment 25 for the reception of sealing wax as indicated by the reference character 26 and a suitable seal 27 and a relatively short longitudinally extending compartment 28 for the 25 reception of paper clips.

A relatively large main compartment 29 is defined by the side wall 12, the rear wall 15, the longitudinally extending partition 18 and the transversely extending partition 20 and 30 this chamber 29 constitutes the filing portion of the cabinet which forms one of the important features of the invention. Arranged in the chamber 29 are a pair of spaced transversely aligned filing pins 30, a rear pair of 35 transversely aligned filing pins 31 and an intermediate pair of transversely aligned filing pins 32. These pairs of pins 30, 31 and 32 are spaced apart substantially equal distances and are connected with the bottom wall 16 in any preferred way, and as shown these pins are firmly held in place by the use of suitable binding nuts 33 which are threaded on the pins in engagement with the opposite faces of the bottom wall. It is to be noted 40 that the openings 17 are formed in the bottom wall in the chamber 29 forwardly of each pair of the pins 30 and 32 and 31. Thus these openings serve the double function of lightening the weight of the cabinet and also to permit the easy removal of record envelopes and 45 the like from off of the said pins.

A cover 35 is provided for the body of the case and this cover is of the same size and shape as the body, the only difference being 50 that the height of the cover is of a less height

than the body of the box or casing. Attention however is invited to the fact that the cover is provided with a longitudinally extending partition 36 and a transversely extending partition 37 which are arranged similarly to the partitions 18 and 19 and abut these partitions forming complete cells when the cover is in its closed position for preventing the displacement of the articles placed in the compartments 26 and 28. The cover 35 is 55 adapted to be held in its raised position, by a suitable toggle link 38 as clearly shown in Figure 2 of the drawings.

The compartment 23 at the front of the casing is adapted to receive the ordinary return receipts 39 utilized in the handling of registered mail and this return receipt is clipped to the registered mail by one of the clips taken from the compartment 28. It is obvious that the mail can be readily handled 80 and sealed and that the arrangement of the compartments 25, 28, 24 and 23 facilitate the handling of the mail and the wax can be readily taken from the compartment 25 and melted by employing one of the matches 85 from the match box compartment 24.

The first pair of filing pins 30 is utilized for the reception of the novel record envelopes 40 and these envelopes are provided with aligned openings to permit the same to 90 be easily placed upon the filing pins. The front face of each envelope is ruled to provide three longitudinally extending parallel lines 41, 42 and 43 and these lines are spaced from the longitudinal edges of the envelopes. 95 Spaced transversely extending lines 44 are also ruled on the envelopes so as to provide a plurality of transversely aligned spaces or columns 45 and these columns bear suitable indicia such as date, contents, amount, post-office receipt number and return card number and these spaces are adapted respectively to receive the date when the registered mail was sent out of the office, the contents of the mail, the amount of bonds or the like contained in the registered package or letter, the post-office receipt number and the like. The space on the front of each envelope above the 100 ruled lines 41, 42 and 43 is also provided with suitable indicia such as record of registered mail from the First National Bank or the like. Below the ruled longitudinal lines, the space left is divided by a transverse line 46 into two sections namely a section 47 and a section 48. This section 47 has printed thereon suitable indicia 49 and blank spaces which are adapted to be filled in by the person handling the registered mail, such as "Insured" 105 "Yes" or "No", the policy number, the report number, passed by, sealed by, registered by, date sent, and the time the package was mailed. The section 48 is adapted to be filled in with the name and address of the person or bank to whom the mail is sent.

The intermediate pair of filing pins 32 is 110

adapted to receive first a pack of binding cards 50, these binding cards being also provided with alined openings to permit the same to be easily placed upon the pin 32. 5 These cards have printed thereon suitable indicia 51 such as "Records of registered mail" and spaces for dates, that the period of time of a particular package of the record envelopes may be readily kept. The pins 32 are 10 also utilized for holding record envelopes at an intermediate stage in the use of the device.

The method of using the improved device is as follows: First a pack of the binding cards 50 is placed upon the pins 32 and a pack 15 of the record envelopes 40 is placed upon the pins 30. One of the binding cards 50 is removed from the pins 32 and is placed face downward upon the rear pair of pins 31. When a registered package or letter is to be 20 sent out one of the envelopes 40 is removed from the front pair of pins 30 and the various spaces on the envelopes are filled in so that a complete record of the package will be had; thus the date when the package is sent is 25 marked on the envelope in the suitable column headed for that data, the contents of the envelope is marked in the contents column such as "L. B." (if the contents be Liberty bonds); the amount of bonds and the like 30 contained in the envelope and the post-office receipt number, the name of the person to whom the parcel is sent. On the portion 47 of the envelope the indicia regarding the packing of the article are filled in such as, by 35 whom it is packed and the time the package was mailed and the like. The envelope which has the data filled in is then placed on the intermediate pair of pins 32 as shown in Fig. 1 and the registering receipt and the like when 40 received is placed thereon. This envelope and receipt remains on the intermediate pins until the return card comes back to the office at which time the number of the return card 45 is filled in at the desired point on the envelope and the card and receipt are placed in the envelope and the envelope is taken off of the pins 32 and placed on the rear pair of pins 31. This process is continued for the desired 50 length of time, say from the first of the month to the fifteenth, after which the envelopes which are on the rear pair of pins 31 are bound together. One of the binding cards 50 is removed from the pin 32 and placed on top of the envelopes which are to be bound so 55 that there will be a binding card at the top and bottom of the pack of envelopes, and both of the binding cards have the date filled in showing the length of time for which the envelopes have been collected. It is to be 60 now noticed that the rear pair of binding pins 31 are of a hollow construction and that the same have the upper faces thereof beveled as at 34 for a purpose which will now be described. When it is desired to bind a pack 65 of the envelopes together, a suitable binding

cord 55 is taken and the terminals thereof are inserted in the said pins 31. The pack of envelopes and the binding cards are now lifted from off of the pins and the binding cord 55 is removed therewith and the terminals thereof will be found threaded through the openings of the envelopes and binding cards. The cord is now tied securely so as to hold the bundle or pack of envelopes together and the same is placed in the bank 75 vault or other place of security.

The improved device can also be used effectively for handling parcel post packages and as shown in Figure 8 I have provided a novel record envelope 60 for this purpose. 80 This envelope 60 is also provided with openings for the reception of the filing pins and the outer face thereof is ruled to provide vertical columns 61, 62, 63, 64, 65, 66, 67, 68 and 69. These columns are adapted to receive the date when the package was mailed, the contents of the package, the C. O. D. receipt number, the insurance receipt number, the amount due the sender, the insurance fee, 85 the cost fee, the post-office fee and the like 90 and the entire total to be paid. The columns are also adapted to receive the exact amount paid and the date thereof and the return receipt number as well as the registered receipt 95 number. Below the columns mentioned the envelope is provided with suitable indicia to show who sent the package and who inspected the same and the time of the mailing thereof and the like. To the left of this indicia is placed the name and address of the person 100 to whom the package is sent. This envelope is utilized exactly in the same manner as the envelopes utilized for registered letters.

From the foregoing description, it can be seen that I have provided a novel device and 105 method of using the same for the effective handling and recording of registered mail and parcel-post packages.

Changes in detail may be made without departing from the spirit or the scope of the invention, but:

What I claim as new is:

1. A device for facilitating the handling and the recording of registered mail, parcel post packages, and C. O. D. packages comprising a filing case including a body provided with a longitudinally extending partition and transversely extending partitions defining a main compartment and independent smaller compartments for the reception of registered return receipt cards, sealing wax, paper clips and the like, certain of said mentioned paraphernalia being adapted to protrude beyond the compartments, spaced pairs of filing pins arranged within the main compartment, a pivoted cover associated with the body for engaging the pins, and partitions carried by the cover for abutting engagement with the partitions arranged in the body for preventing the displacement of 115 120 125 130

matter disposed in the compartments of the body incident to the carrying of the case.

2. A file box for handling registered mail, parcel post packages, and C. O. D. packages comprising a box provided with a main compartment, a plurality of record envelopes having record indicia printed thereon for the reception of registry receipts, filing pins for initially receiving said envelopes, a bind-

ing card having record indicia printed thereon, filing pins for normally receiving the binding card, and filing pins for receiving the binding card and the record envelopes upon the receipt of the registry return cards all of said pins being carried by the box and disposed in the main compartment. 10 15

In testimony whereof I affix my signature.

FRANK VOGEL.
